UNITED STATES PATENT OFFICE.

JOHN THOMPSON, OF VICTORIA, BRITISH COLUMBIA, CANADA.

LIFE-PRESERVER.

SPECIFICATION forming part of Letters Patent No. 240,785, dated April 26, 1881.

Application filed September 30, 1880. (No model.)

To all whom it may concern:

Be it known that I, JOHN THOMPSON, of Victoria, in British Columbia and Dominion of Canada, have invented a new and Improved 5 Life-Preserver, of which the following is a specification.

The invention relates to that class of devices designed to be placed about the body to support and float persons in the water.

10 The invention consists of a series of floats so hinged to a belt that is to be fastened around the body that when not in use the floats hang perpendicularly from the belt, and when the device is in use the floats extend radially and 15 at right angles from the belt and lock themselves in position; and it consists, further, of a circular water-proof covering enveloping the series of floats, which envelope may be inflated; and, further, of a filling of cork between 20 the floats within the envelope, all of which is hereinafter described.

Figure 1 is a front view of the device with the belt unbuckled and stretched out. Fig. 2 is a plan of the same with the belt buckled in 25 position for use. Fig. 3 is a plan of the device with an air-tight and water-proof covering. Fig. 4 is a plan of the same with a water-tight covering and with cork filled in between the floats. Fig. 5 is an enlarged sectional side elevation of a float on line *xx*, Fig. 2. Fig. 6 is a sectional elevation on line *yy*, Fig. 4. Fig. 7 is a sectional side elevation of a hollow metal float.

Similar letters of reference indicate corresponding parts.

In the drawings, A represents the belt, designed to be about five inches wide, and provided on its face with a series of metallic plates, *a a*, secured at equal distances apart. Near 40 the upper edge of each plate *a* an aperture, *b*, is made, that extends through the belt A, and immediately over these apertures *b b* narrow plates *c c* are secured, that project downward partly over the apertures *b b* and serve as 45 catches for the hooked ends of the hooks *d d*, that are attached to the floats B B. Said floats B B are hinged to the plates *a a*, as shown at *d' d'*, and are made of a central cork, *f*, covered with top and bottom plates, *g*, of wood, that 50 are held in place by bolts *h*, that pass vertically through both plates and cork *g f*. These floats B B are designed to be about ten inches long,

between four and five inches across at their outer ends, between two and three inches across at their inner ends, and to weigh from six to 55 twelve ounces each, and are preferably made to taper flatwise. On the upper face of each float B a spring-hook, *d*, is secured, consisting of a flat strip of metal with a hooked free end, whose free end, when the floats B B are in the 60 position shown in Figs. 2, 3, 4, 5, engages in an aperture, *b*, and under the edge of a plate, *c*, whereby said floats B B are held in a horizontal position. The belt A is provided with straps *k* and buckles *l* at opposite ends, for 65 fastening the device about the person; but clasps or other suitable devices may be used for this purpose, and an alarm-rattle, *F*, similar to a watchman's rattle, is attached to said belt A by a cord or chain, *F'*, as shown in Fig. 70 1, whereby a noise may be made by the operator that will be heard at a greater distance than the human voice, and can be distinguished from all other sounds, thereby increasing the 75 chances of safety or rescue to the wearer of the life-preserver.

A life-preserver of the above construction will easily support a weight of about one hundred and fifty pounds in the water; and if it be buckled about the body, just beneath the 80 arms, it will keep the head and shoulders of a person of such weight well above the water.

In Fig. 3 is shown the device represented by Figs. 1 and 2 inclosed in an air-tight covering, C, of rubber cloth or other suitable fabric, and 85 in this instance the radial opening *m* in the device is closed, or the edges of the covering C are brought near to each other and held in position by straps and buckles *n n*. D represents a flexible tube attached to the device for 90 the purpose of inflation. In Figs. 3 and 4 the same device of floats B B is represented inclosed in a water-proof envelope, C, strapped together by straps and buckles *n n*, and with pieces of cork, E, packed within said envelope 95 C, between the floats B B, to increase the buoyancy of the device. Either of these devices shown in Figs. 3 and 4, with floats B B of same dimensions and construction as those shown in Figs. 1 and 2, will easily support two persons 100 in the water.

In Fig. 7 is shown a float, B, of modified construction, it being an air-tight metal box.

When not in use this life-preserver occupies

but little space, can be conveniently carried in a hand-valise, and it is strong, durable, and easy of adjustment, and when secured to a person in the water said life-preserved spreads out 5 horizontally on the surface of the water and affords a perfect support for the body and a rest for the arms. When it is provided with an air-tight covering, as shown in Fig. 3, it will support a person in the water until, at his 10 leisure, he may inflate the covering, and when inflated it will afford ample support to a second person.

Having thus fully described my invention, I claim as new and desire to secure by Letters 15 Patent—

1. A life-preserved constructed substantially as herein shown and described, consisting of belt A, having suitable fastenings and provided with perforated plates *a a* and catches *c c*, and hinged floats B B, provided with spring- 20 hooks *d d*, arranged and operated as set forth.

2. The combination, with the belt A, adjustable hinged floats B B, and envelope C, of the cork filling E, substantially as and for the purpose described.

JOHN THOMPSON.
